PLANTER

Gilbert C. Frenz, Milwaukee, Wis.

Application October 28, 1953, Serial No. 27,359

Term of patent 3½ years

(Cl. D35—3)

To all whom it may concern:

Be it known that I, Gilbert C. Frenz, residing in Milwaukee, in the county of Milwaukee, State of Wisconsin, have invented a new, original, and ornamental Design for a Planter, of which the following is a specification, reference being had to the accompanying drawing, forming a part hereof.

I claim:

The ornamental design for a planter, as shown.
